UNITED STATES PATENT OFFICE.

LAWRENCE LIPPI, OF NEW YORK, N. Y., ASSIGNOR TO R. W. AUBÉ & SON,
OF SAME PLACE.

DESIGN FOR MOLDING FOR PICTURE-FRAMES, &c.

SPECIFICATION forming part of Design No. 23,904, dated December 25, 1894.

Application filed November 26, 1894. Serial No. 530,053. Term of patent 3½ years.

To all whom it may concern:

Be it known that I, LAWRENCE LIPPI, a subject of the King of Italy, residing at New York, in the county of New York and State 5 of New York, have invented and produced a new and original Design for Picture-Frame Moldings and the Like, of which the following is a specification, reference being had to the accompanying drawings, forming part 10 thereof.

Figure 1, is a view of a molding showing my design. Fig. 2, is a corner of the same.

My design consists in the ornamentation of leaves and parts of leaves which are raised up, 15 and project above the base of the molding, all the ornamentation being in relief. The parts are arranged as shown in the accompanying drawings.

My design is suitable for picture frames 20 and the like.

A are the large leaves or leafy ornaments in relief which occupy the full width of the molding, and are placed in opposite direction 25 in regard to each other. Between the leaves A, there is a leafy ornamentation as shown at

B, which is raised and projects inwardly toward the base of the molding as shown. There is an ornament at the end of the molding composed of leaves or parts of leaves as shown at C which is raised up from the base 30 of the molding as shown. Leaves or parts of leaves are placed on the base of the molding as shown at D. The corner is formed of leaves all in relief which project upwardly and inwardly toward the center of the molding as 35 shown at E.

The leading features of my design are the leafy ornaments A, and the leafy ornaments B between them, which ornaments project outwardly and inwardly toward the center of 40 the molding substantially as shown, all being in relief.

What I claim is—

The design for a molding for picture frames and the like, substantially as herein shown 45 and described.

LAWRENCE LIPPI.
